UNITED STATES PATENT OFFICE.

PATRICK P. McHUGH, OF BROOKLYN, NEW YORK.

DESIGN FOR VISITING-CARDS.

SPECIFICATION forming part of Design No. 11,718, dated April 6, 1880.

Application filed February 18, 1880. Term of patent 3½ years.

To all whom it may concern:

Be it known that I, PATRICK P. McHUGH, a citizen of the United States, residing at Brooklyn, in the county of Kings and State of New York, have invented and produced a new and original Design for Visiting-Cards, Tablets, and similar devices, of which the following is a specification.

The nature of my design is fully represented in the accompanying drawing, to which reference is made.

A is the base or body of the card, which may be of any desired color. B is a turned-over portion or lapel, which is provided with a perforation, C, adapted to expose a portion of the main card A through the turned-over portion or lapel B. Through the hole or perforation C is turned or affixed a bow or knot, D.

I prefer that the parts A and B shall be of different colors or shades of color, or they may be both of one tint.

Upon the part A, I can inscribe, engrave, print, or otherwise affix any suitable designs, writing, photographs, or pictures.

Suitable designs, writing, photographs, or pictures may be applied on the part B.

Dates, monograms, or other devices may be exposed through the perforation or aperture C.

I claim—

1. The design for cards, tablets, and similar devices, consisting of a main body, A, having a turned-over portion or lapel, B, and perforation or aperture C, substantially as shown and described.

2. The design for visiting-cards, tablets, and similar devices, consisting of a main body, A, having a turned-over portion or lapel, B, perforation or aperture C, and bow or knot D, as shown in the accompanying illustration.

PATRICK P. McHUGH.
